His Atty.

UNITED STATES PATENT OFFICE.

CHARLES MORGAN, OF FREEPORT, ILLINOIS, ASSIGNOR TO THE ARCADE MANUFACTURING COMPANY, OF SAME PLACE.

MOP-HEAD.

SPECIFICATION forming part of Letters Patent No. 553,354, dated January 21, 1896.

Application filed June 28, 1895. Serial No. 554,347. (No model.)

To all whom it may concern:

Be it known that I, CHARLES MORGAN, a citizen of the United States of America, residing at Freeport, in the county of Stephenson and State of Illinois, have invented certain new and useful Improvements in Mop-Heads, of which the following is a specification.

My invention relates to certain improvements in mop-heads; and it consists in a certain new construction fully described below and pointed out in the appended claims.

The drawings presented herewith show my preferred construction by means of two figures, of which—

15 Figure 1 is a side elevation of the same, and Fig. 2 is a section in line 2 2 of Fig. 1.

In the drawings, A is a mop-handle terminating in a cross-head B, against which the mop-rags are to be held by means of a wire 20 loop C, the lower horizontal portion of which is opposed to the cross-head B when the rags are clamped in position. The loop C is preferably composed of wire bent to form a horizontal portion c, end portions c' c'', which slide

25 vertically and are guided by means of slight sockets b b' in the opposite ends of the head, and hooks c' c'', which are bent inward and upward and engage with eyes d upon a collar D, which encircles the handle and is sufficiently large to move freely thereon. Within

30 this collar is a ratchet-lever E, provided at one end with a hook e, which hooks into an eye b' upon the cross-head B, and the other end of the lever is formed into a handle e' which is pressed away from the mop-handle

35 by means of a coiled spring e'', held in place by a lug e''' beneath the lever-handle e' at one end,

and at the other end by a socket a in the handle proper, A.

Upon the outer side of the lever E are a series 40 of ratchet-teeth e' adapted to engage an in-turned point or edge d' upon the collar D.

In operation the loop C is held in any desired position by means of the ratchet-lever E, which engages with the collar D. This engagement, however, may be released by pressing inward upon the lever-handle e' and the position of the horizontal portion c of the loop C regulated at will.

I claim as new and desire to secure by Letters Patent—

1. The combination in a mop-head, of the handle, A, the cross-head, B, the collar, D, the loop, C, having the horizontal portion, c, the end portions, c', c'', and hooked to the 55 collar, D, the ratchet lever, E, hinged to the cross-head and provided with ratchet teeth to engage the collar, and a spring interposed between it and the handle to keep up the engagement between the lever and the collar; 60 substantially as described.

2. The combination with the handle, A, of the cross head, B, having the end sockets, b, b', and eye, b'', the lever, E, having the hook, e, and the ratchet teeth, e', the spring, e'', the 65 loop, C, the collar, D, having ears, d, to which the ends of the loop are hooked, and a tooth, or edge, d', adapted to engage the ratchet teeth, e'; substantially as described.

CHARLES MORGAN.
